UNITED STATES PATENT OFFICE.

WALTER SYLVESTER, OF TUNSTALL, STOKE-UPON-TRENT, ENGLAND.

PAWL-AND-RATCHET MECHANISM.

1,173,325.

Specification of Letters Patent. Patented Feb. 29, 1916.

Application filed October 30, 1913. Serial No. 798,318.

To all whom it may concern:

Be it known that I, WALTER SYLVESTER, a subject of the King of Great Britain and Ireland, and resident of Tunstall, Stoke-upon-Trent, Stafford, England, have invented certain new and useful Improvements in or Applicable to Pawl-and-Ratchet Mechanism, of which the following is a specification.

10 This invention relates to improvements in lifting, hauling or straining appliances of the kind in which a lever and pawls are used in conjunction with a toothed wheel or wheels to operate a drum, pulley, or chain 15 block wheel.

The objects of the improvements are, first, to enable the reverse movement of said appliances to be effected by a simple adjustment which permits of the operating lever 20 being worked in a similar manner either when hauling or lowering, the lowering or releasing being effected tooth by tooth; second, to provide means whereby the coils of 25 rope, cable, chain, or the like may be kept tight and even on the drum or pulley; third, to provide means for preventing the drum or pulley being unwound too far so as to cause damage to the rope or cable by the backward bending action which may result; and, 30 fourth, to provide means for enabling any ordinary mechanic to replace the old rope with a new one.

The objects are attained by the mechanism illustrated in the accompanying drawings in which the improvements are shown in connection with a drum suitable for use with a flexible wire rope or the like and to which drum are attached two side plates or disks having ratchet teeth on their peripheries.

Figure 1 is a front side elevation showing the pawls engaging with the ratchet teeth when about to wind the rope or cable upon the drum, the reversing mechanism being 45 out of action until it is required to lower or release the load. Fig. 2 is a plan of Fig. 1 looking from the underside. Fig. 3 is a sectional side elevation of the lower portion of Fig. 1 showing the reversing mechanism in 50 action. Fig. 4 is a similar view to Fig. 3 showing the position of the lever at the beginning of the lowering stroke. Fig. 5 is a sectional side elevation of the drum showing the method of attaching the end of the 55 rope or cable to the inside of the drum. Figs. 6 and 7 are illustrative of a modified

form of rope or cable securing means. Fig. 8 is a cross-sectional elevation of the upper portion of Fig. 1 showing position of rope cap and the stop wheels, which latter are 60 also shown in broken lines in Fig. 5. Fig. 9 is an end elevation showing the means for keeping the rope even on the drum.

Similar letters refer to similar parts throughout the several views.

The drum *a* and the toothed wheels or ratchet disks *b*, *b* with pawls *c'*, *c*² mounted between the side cheeks or plates *d*, *d* are carried by the shaft or spindle *e*.

In carrying the present invention into 70 practice a lever *f*, hereinafter referred to as the reversing arm, fulcrumed at *f'*, is fitted into the frame of the machine for the purpose of lifting the pawls *c'*, *c*² out of engagement with the teeth, as each pawl is alternately relieved of the pressure of the load upon it, and for the further purpose of alternately holding the said pawls free from the ratchet wheels until the latter have rotated sufficiently to allow one or other of the 75 pawls to engage with the next succeeding tooth. The arm *f* is provided with two studs or pins *g'*, *g*², or two pairs of studs, which engage with the inner surface of the pawls, while springs *h'*, *h*² serve to bear on the 80 pawls and arm, respectively, to set up an opposing force between the pawls and arm, as will hereinafter be more fully understood. To the stud *g'* is connected one end of the spring *h'* and to the stud *g*² is connected by means of the link *h*³, one end of the spring *h*², while the other ends of said springs are respectively connected to the pawl fulcrums.

During the time that the machine is lifting or drawing a load the reversing arm *f* is kept out of operation by a small eccentric cylinder *i* carried by the spindle *i'*. To the eccentric *i* is fitted a small handle *i*² by which the eccentric may be rotated when 100 requiring to bring into action the reversing mechanism.

The method of unwinding is as follows:— The handle *i*² is turned round from the position shown in Fig. 1 to the position shown in Fig. 3, so that the eccentric part of the cylinder *i*, which before held the reversing arm studs or pins *g'*, *g*² clear of the pawls *c'*, *c*², lies out of contact with the reversing arm and allows the arm, through its studs *g'*, *g*² 110 to act alternately upon each of the pawls *c'*, *c*². Therefore, as the operating lever or

handle j is moved backward in the direction of the arrow x the pressure upon the retaining pawl c' is removed, and the reversing arm f immediately lifts the pawl c' out of its notch to hold it clear until the point of the back tooth has passed. As the handle j is moved forward in the direction of the arrow y the projection or swelling c^3 formed on the inside of the pawl c^2 comes into contact with the stud g^2 , and the movement exerted by the said projection, as the pawl c^2 is drawn past the stud g^2 , causes the arm f to be forced toward the drum which therefore removes the outward force exerted upon the pawl c' , and causes it to fall into the next notch ready to take the pressure of the load from the pawl c^2 , as soon as the lever j shall have described the necessary arc to allow the drum to rotate sufficiently to bring the next tooth into contact with the pawl c' .

It will be understood that one pawl can only be affected by the reversing arm f during the period that the other pawl is bearing the pressure of the load. As soon as the pawl c' has taken the pressure from the pawl c^2 the arm f immediately lifts the latter named pawl out of its notch or tooth and holds it clear until the pawl c^2 has been moved backward in the direction of the arrow x a sufficient distance to bring the stud g^2 from the raised portion c^3 of the irregular profile, formed on the inner surface of the pawl c^2 , to the depression c^4 . When the stud g^2 has entered into the depression c^4 the stud g' comes into contact with the bottom of the depression c^5 formed in the pawl c' , see Fig. 4. This holds the stud g^2 clear of the pawl c^2 and allows said pawl to fall into the next notch which it has now reached, see Fig. 4. As soon as the pawl c^2 reaches the next tooth the pressure of the load is removed from the pawl c' to the pawl c^2 and the operation is again repeated until the load has been sufficiently lowered or released.

In order that the coils of rope or cable shall wind evenly and keep tight upon the drum a , a plate or frame k is hinged upon a pin k' , see Figs. 1 and 9, and forced against the periphery of the drum by a spring l , while a roller m fitted to the plate k serves to reduce friction on the rope. When the rope or cable is being unwound quickly there is a danger, immediately the last coil is run off, of the rope or cable being subjected to a bending action which in time would seriously damage the rope or cable. To prevent this toothed wheels n' , n^2 , similar to those used in the overwind actions of clocks, are mounted on the drum and frame respectively, see Fig. 5. The stop action of the wheels n' , n^2 is brought about by the wheel n^1 having a shallow notch n^3 and the wheel n^2 having one tooth n^4 larger than the remaining teeth. The wheels are also made of sufficient size and pitch, proportionately, to

allow the drum to make the requisite number of revolutions before the large tooth n^4 shall engage with the shallow notch n^3 to bring about the stoppage.

To enable an ordinary mechanic to replace the wire rope or cable, it is fitted and supplied with a cap or socket o made to the curvature of drum. The cap or socket is capable of being riveted, or otherwise secured, to the drum at o' , and of abutting against a shoulder or projection a' on the drum. In a modification the cap or socket o may be hinged to a spindle p passing through the drum a , see Fig. 6. With this last named method of attachment the fixing and detaching of the rope or cable will be greatly facilitated, and the stop wheels n' , n^2 may be dispensed with.

The above described method of fixing the rope or cable also serves to distribute the weight of the load more equally upon each of the wires constituting the rope where there is a weakness near the cap. The object is still further attained by capping the rope when the rope and cap are placed in the same curved position as it will occupy when fitted to the drum. It is also preferable that the wires of the rope be secured in the cap by a filling of white metal or other suitable alloy.

Although the use and application of a wire rope or cable is shown it is to be understood that a chain or the like may be employed in connection with the improvements.

What I claim is:

1. In pawl and ratchet mechanism, a frame, a ratchet wheel axially mounted in said frame, a retaining pawl and an actuating lever pivotally mounted in said frame, an advancing pawl pivotally connected to the operating lever, means for urging the pawls into engagement with the ratchet wheels, and means for retracting the advancing pawl, said means being controlled by the advancing pawl so as to retract the retaining pawl when said advancing pawl is in engagement with the ratchet wheel.

2. In pawl and ratchet mechanism, a frame, a ratchet drum axially mounted in said frame, a pawl pivoted on a stationary pivot, a second pawl pivoted on a movable pivot, means for advancing and retracting said movable pivot, means for urging the pawls into engagement with the ratchet drum, spring actuated means for retracting the second pawl at one end of its stroke, controlled by said pawl at the end of its stroke to retract the first pawl substantially as herein set forth.

3. In pawl and ratchet mechanism, a frame consisting of two flat plates lying parallel to each other and at a slight distance apart, cross-stays holding the plates securely to each other and at the required distance apart, a spindle extending from plate

- to plate, a ratchet drum rotatably mounted on said spindle, a lever handle pivotally mounted between the plates of the frame, a pawl also pivotally mounted between the 5 plates of the frame, a second pawl pivotally mounted on the lever handle, and means for urging both pawls into engagement with the ratchet drum, a spring actuated lever arm pivotally connected to the frame and 10 connected with the pawls for alternately retracting said pawls, substantially as herein set forth.
4. Pawl and ratchet mechanism comprising a frame, a ratchet drum axially mounted 15 in said frame, a pair of pawls adapted to engage the teeth of the ratchet drum, a lever handle pivotally secured to the said frame, one of the said pawls being pivotally mounted in the said handle and the other 20 of said pawls being pivotally mounted in the said frame, a lever arm pivotally mounted in the frame and having lateral studs near its free end engaging one pawl, and further lateral studs near its pivoted end which 25 engage the other pawl, a coiled wire spring encircling the pivot of each pawl, a link pivotally connecting the end of the said lever arm to one end of the spring around the pivot of the lever handle pawl, the other end of 30 the same spring urging the pawl into engagement with the ratchet drum and the ends of the spring around the pivot of the other pawl respectively pressing against said pawl and the lever arm, recesses in the before 35 mentioned pawls to receive the lateral studs on the pivoted lever, the recess in the pawl pivoted to the operating handle being shaped to govern the action of the before mentioned pivoted lever upon the other 40 pawl, substantially as herein set forth.
5. In pawl and ratchet mechanism, a frame consisting of two flat plates lying parallel to each other and at a slight distance apart, cross-stays holding the plates securely to each other and at the required distance 45 apart, a spindle extending from plate to plate, a ratchet drum rotatably mounted on said spindle, a lever handle pivotally mounted between the plates of the frame, a pawl also pivotally mounted between the 50 plates of the frame, a second pawl pivotally mounted on the lever handle, and means for urging both pawls into engagement with the ratchet drum, a spring actuated lever arm pivotally connected to the frame and provided with lateral projections to contact 55 with recesses in the inner face of the pawls to alternately retract the same, a spindle and cam revolvably mounted in the said frame, an operating handle for said spindle whereby the cam may be turned in one direction to move the lever toward the ratchet drum, with its studs clear of the pawls to allow 60 said pawls to act independently, or in the opposite direction to allow the lever arm to 65 recede from the ratchet wheel and the studs approach the pawls to insure inter-action substantially as herein set forth.
6. Pawl and ratchet mechanism comprising a frame a ratchet wheel axially mounted 70 in said frame, a pair of pawls adapted to engage the teeth of the ratchet drum, one of said pawls being pivotally connected to an operating handle and having a recess on one of its faces, deeper at the end next the hub of 75 the pawl than at the other end and the bottom face of the recess being sloped and undulating, and means for retracting said pawls which engage the said recess to govern the retraction of the retaining pawl substantially as herein set forth.

In witness whereof I have hereunto set my hand in the presence of two witnesses.

WALTER SYLVESTER.
